UNITED STATES PATENT OFFICE.

WILLIAM S. ATWOOD, OF MONTREAL, QUEBEC, CANADA, ASSIGNOR TO CANADIAN CAR & FOUNDRY COMPANY, LIMITED, OF MONTREAL, CANADA.

ORE-CAR.

1,123,655.

Specification of Letters Patent.

Patented Jan. 5, 1915.

Application filed February 7, 1913. Serial No. 746,748.

To all whom it may concern:

Be it known that I, WILLIAM S. ATWOOD, of the city of Montreal, in the Province of Quebec and Dominion of Canada, have invented certain new and useful Improvements in Ore-Cars, of which the following is a full, clear, and exact description.

This invention relates to improvements in ore cars, and the object is to provide a hopper per car so constructed that the door opening, which is in the floor of the car, will be absolutely unobstructed between the trucks of the car.

A further object is to provide a hopper car having the under frame so arranged that the door opening will not be obstructed by the center sill of the car.

In hopper cars for handling ore, coke, or even coal, it has been found that the discharge opening when cut into a number of small door openings by the intersecting center sills and transoms or bolsters does not discharge the lading of the car as quickly or as speedily as might be desired, as the material tends to catch on the members forming the door frames and jambs, so that the discharging operation is retarded. The present invention aims to overcome this disadvantage by providing a car so arranged that the door opening, which occupies the entire floor and is a considerable part of the entire width of the floor, is absolutely unobstructed between the trucks, so that the largest lumps or the roughest class of material will escape without hindrance.

In the drawings which illustrate the invention, and throughout the several figures of which similar numerals refer to corresponding parts: Figure 1 is a half vertical sectional view on the longitudinal center of a car. Fig. 2 is a half plan view showing in the upper portion the body and in the lower portion the under frame. Fig. 3 is a half end elevation. Fig. 4 is a half transverse section on the line 4—4 of Fig. 1. Fig. 5 is a partial transverse section on the line 5—5. Fig. 1. Fig. 6 is an enlarged transverse section on the line 5—5, showing the arrangement of the door.

Referring more particularly to the drawings, 11 designates the center sills as a whole and 12 the body bolsters. The center sills are formed in three parts, namely, the central portions 13, which are widely spaced apart and are attached at their extremities

to the body bolsters. The second and third parts of the sills are the two end portions 14, which are spaced approximately the usual distance apart and are attached to the opposite side of the bolsters from the central portions 13. It will thus be seen by a glance at Fig. 2 that at the ends of the car the arrangement of underframe is very much of the ordinary type, but that the sills are spread apart at the center of the car, so as to provide for a large unobstructed door opening. Side sills 15 are provided and are connected at suitable intervals with the center sills by cross beams 16. These side sills also connect to the ends of the bolsters and are connected at their adjacent extremities by end sills 17, which intersect the end portions 14 of the center sills and are attached thereto. Gusset plates 18 are provided at the junction of the side and end sills, and similar plates 19 are provided at the junction of the end portions of the center sills with the bolsters. Diagonal braces 20 of suitable section are provided to connect the plates 18 and 19. These braces prevent any possible relative movement between the sides and center sills and greatly stiffen the car.

The body, designated as a whole by the numeral 21, consists of vertical side portions 22, which extend from the top of the body approximately half way downward to the side sills. The lower edges of the vertical portions 22 are connected to sloping portions 23, which are inclined at an angle of approximately 45°, and terminate just below and inside the middle portions of the center sills. The ends 24 of the body are sloped continuously from the upper to the lower edge.

The corners of the body are supported by vertical angles 25 which rest on the corners of the underframe. The upper portions of the body sides are supported and held against bulging by the side stakes 26, which are attached at their lower ends to the side sills. The sloping portions of the sides are stiffened by angles 27 riveted thereto, and attached at their upper extremities to the side stakes and at their lower extremities to the upper portions of stiffening plates 28. These stiffening plates 28 are vertically disposed and are attached to the portions 13 of the center sills from top to bottom thereof, and are again attached to the cross beams 110

16. The sloping ends of the body are supported at their lower ends by vertically disposed plates 29 which extend between the center sills. The ends are again supported 5 approximately at their centers by vertical plates 30, the lower edges of which are secured to the body bolsters 12. The vertical ends of the plates 30 are connected to the first pair of side stakes, as will be easily 10 seen in Figs. 1 and 2, and thus provide a very rigid support for the body.

It will be seen from the drawings that the door opening, designated 31, extends transversely from center sill to center sill, and 15 longitudinally between the plates 29, which it will be noted are disposed practically over the rear and front axles of the front and back trucks respectively. This opening is absolutely unobstructed by either longitudinal 20 or transverse members, so that when the doors 32 are opened there will be nothing to interfere with the discharge of the lading. The doors 32 are for convenience preferably two in number, and each consists 25 of a flat plate slightly larger than the door opening, so that the edges of the plate project under the lower edges of the sides and ends. These doors are suitably stiffened by angles 33, and are hinged at one longitudinal 30 edge upon pins 34 carried by stiffening plates 35 secured to one center sill.

At the ends of the door opening, the transverse members 29 are provided which connect the center sills. These members provide support for a creeping shaft 37, which extends from end to end of the car. At the center of the car, this shaft is supported by a small bracket 38. When two doors 32 are used, the shaft 37 may be divided at the center 40 of the car, so that the doors can be operated independently. At suitable intervals the free edges of the doors are provided with rack toothed castings 39, which mesh with pinions 39 mounted upon the shaft 37. Attached to each pinion is a worm or other suitable chain guide 40. Chains 41 are provided and are connected at one extremity to the free edge of the doors and at the opposite extremity to the guides 40. When 45 the shaft is rotated in the direction of the arrow, Fig. 6, it winds up the chains and raises the doors 32 to horizontal position, the shaft remaining in the pockets 42 at the outer ends of the slots 43. Continued revolution draws the shaft under the edges of the doors so that the pinions 39 engage the rack members 38 on the doors and travel to a position well under the edge of the doors, whereby the doors are firmly supported. Any suitable mechanism 44 is provided at the ends of the car to rotate the shaft and to hold the same against revolution. To dump the contents of the car, the shaft 37 is rotated in a reverse direction and 60 by reason of the pinions meshing with the

rack members, the shaft travels out from under the edge of the doors so that the doors are released, the shaft falling into the pockets 42 and there being rotated by the unwinding of the chain due to the weight 70 on the doors 32. The mechanism 44 at the ends of the car may be of such nature as to check the too rapid rotation of the shaft.

Having thus described my invention, what I claim is:—

1. A car of the type described including an underframe having an extended discharge or lading opening centrally of the car, a door forming the car floor hinged to one side of said opening, and a creeping shaft arranged to the opposite side of said opening to hold said door closed. 75

2. A car of the type described including an underframe having center sills, spaced apart to form an extended discharge or unloading opening centrally of the car, a closure forming the car floor hinged to one of said sills, and a creeping shaft carried by the other center sill to hold said closure in closed position. 80

3. A car of the type described including an underframe having center sills spaced apart to form an extended discharge or unloading opening centrally of the car, a door or closure forming the car-floor hinged to one of said sills, a creeping shaft carried by the other center sill to hold said closure in closed position, and shaft and gear mechanism flexibly connected with said creeping shaft for actuating the same. 90

4. In a car of the character described, an underframe comprising a pair of center sills spaced more widely apart between the car trucks than at the extremities thereof, a body mounted on said sills having sloping sides and ends converging into the space between the center sills, a door forming the car floor hinged to one center sill, and a creeping shaft carried by the other center sill arranged to hold said door in closed position. 105

5. In a car of the character described, an underframe comprising a pair of bolsters, a pair of center sills spaced more widely apart between said bolsters than beyond the bolsters, a body mounted on the under frame having sloping sides and ends converging into the unobstructed space between said center sills and bolsters, a floor door extending from side to side of the body hinged to one center sill, a creeping shaft carried by the other center sill and movable to a position under the door to support the same, stiffening members secured to the center sills, and inclined extensions from said members supporting the sloping sides of the car. 115

6. In a car of the character described, a pair of center sills having the central portions thereof offset toward the sides of the car, a body having sloping sides and ends 120

mounted on said sills, a floor door forming the bottom of said body hinged to one center sill and extending across the car to the other center sill, means carried by said second center sill for supporting the free edge of the door, a pair of side sills, cross beams connecting the side and center sills, stiffening members connecting the center sills and cross beams, inclined extensions of said 10 stiffening members supporting the sloping sides of the body, side stakes carried by said

side sills supporting the upper extremities of said inclined members, and vertical plates mounted on the bolsters and supporting the sloping ends of the body.

15

In witness whereof I have hereunto set my hand in the presence of two witnesses.

WILLIAM S. ATWOOD.
